UNITED STATES PATENT OFFICE.

HENRY FLICK, OF JACKSON, MICHIGAN, ASSIGNOR TO HAYES WHEEL COMPANY, OF JACKSON, MICHIGAN.

PROCESS OF MANUFACTURING SPOKES.

Application filed October 4, 1921, Serial No. 505,243. Renewed August 1, 1923.

To all whom it may concern:

Be it known that I, HENRY FLICK, a citizen of the United States, residing at the city and county of Jackson, State of Michigan, have invented certain new and useful Improvements in Processes of Manufacturing Spokes, of which the following is a specification.

This invention relates to a process of manufacturing spokes.

The object of the invention is to provide a complete spoke with tapered head and tenon ready for use.

Objects relating to details and economies of construction and operation will definitely appear from the detailed description to follow.

The objects of the invention are accomplished by the devices and means described in the following specification. The invention is clearly defined and pointed out in the claims.

A structure which is a preferred embodiment of the invention is fully illustrated in the accompanying drawing, forming a part of this application, in which:

Figure I is a detail view of a billet illustrating the first step of this invention.

Fig. II is a view illustrating the turning and finishing step of the spoke.

Fig. III is a view of the spoke with all parts, including the tenon, formed complete.

In the drawing similar numerals of reference refer to similar parts throughout the several views.

Considering the numbered parts of the drawing by their numbers, 1 is the spoke billet which is first dressed straight on one side and one edge, which are used as references, and then forming the tapered inner head 2 at the end of the spoke. The tapered head is then chucked in a spoke turning lathe, the tapered dressed face thereof being made use of as reference when the entire body of the spoke 3 is turned with the flaring portion 4 at the inner head end, as seen in Fig. II.

An annular groove at 5 is then cut forming the incomplete tenon with a button 5' left at the end. The entire turned surface of the spoke is then engaged including the periphery of the button 5', which supports the sanding belt and insures a perfectly square finish of the outer end of the spoke.

When the finishing process is complete

the end of the tenon is cut off at 6. The tenon here shown has a rounded shoulder, as seen at 5'', which is the kind preferred for use with metal fellies.

Where the spoke is used with wood fellies the shoulder of the tenon 6 should be cut square.

Of course for rough work the sanding step of this process might be omitted, but is desirable for the smoothest work.

Where a spoke is made and finished in this way a perfect wheel is produced which requires no dressing or finishing between the spokes at the center of the wheel, which is a usual expedient to secure a nicely finished wheel, but with this invention the wheel presents a more satisfactory appearance without any such rasping or cutting having been done at this point, and very little facing is necessary.

While this spoke is shown turned perfectly round, the method is applicable to spokes of irregular cross section.

Having thus described the invention, what is claimed as new and desired to secure by Letters Patent, is:

1. The process of manufacturing spokes comprising the finishing of one face and edge of the billet, then using these parts as reference forming a tapered inner head on the billet, then chucking the tapered inner head and using it as reference and turning the body of the spoke and extension thereof, cutting an annular groove near the outer end of the spoke to form the spoke tenon, sanding and dressing the outer turned portion of the spoke including the full projecting end, then cutting off the outer end of the tenon, as specified.

2. The process of manufacturing spokes comprising the finishing of one face and edge of the billet, then using these parts as reference forming a tapered inner head on the billet, then chucking the tapered inner head and using it as reference and turning the body of the spoke and extension thereof, cutting an annular groove near the outer end of the spoke to form the spoke tenon, then cutting off the outer end of the tenon, as specified.

3. The process of manufacturing spokes comprising forming a tapered inner head on the billet, then chucking the tapered inner head and using it as reference and turning the body of the spoke and extension

thereof, cutting an annular groove near the outer end of the spoke to form the spoke tenon, sanding and dressing the outer turned portion of the spoke including the full projecting end, then cutting off the outer end of the tenon, as specified.

4. The process of manufacturing spokes comprising forming a tapered inner head on the billet, then chucking the tapered inner head and using it as reference and turning the body of the spoke and extension thereof, cutting an annular groove to form

the spoke tenon, and then cutting off the outer end of the tenon, as specified.

5. The process of manufacturing spokes 15 comprising forming a tapered inner head on the billet, then chucking the tapered inner head and using it as reference and turning the body of the spoke and extension thereof, and cutting an annular groove to 20 form the spoke tenon, as specified.

In witness whereof, I have hereunto set my hand and seal.

HENRY FLICK. [L. s.]
